POWER-OPERATED BOTTLE OPENER

Filed Nov. 18, 1948

FIG. 2

UNITED STATES PATENT OFFICE

2,612,065

POWER-OPERATED BOTTLE OPENER

Donald H. Packer and Peter R. George, Toledo,
Ohio; said George assignor to said Packer

Application November 18, 1948, Serial No. 60,682

5 Claims. (Cl. 81—3.2)

1

This invention relates to dispensing from containers, and more particularly to releasing and positively removing flanged disk type of sealing caps from liquid containing bottles.

This invention has utility when incorporated in a grab or multiple jaw type of grapple in a power actuated device for pull-off and release in decapping bottles, wherein there is an inward gripping at the bottle top lip under side by a fluted or corrugated rim or flange of a closure disk. In accordance with the invention, this depending bent flange is caught at spaced points while its center is pulled upward and held for the engaged portions to be flared outwardly and thus have the bottle closure positively pulled clear of the container. The pulled-off flanged disk closure as thus distorted clear of the bottle, is then ejected from the tool, as the decapper is automatically reset for a repetition of the operation cycle, effected by merely thrusting the next cap-closed bottle upward to effect electric switch closing.

Referring to the drawings:

Fig. 1 is a front view of an embodiment of the invention incorporated in a unit adapted to be mounted on a wall;

Fig. 2 is an enlarged view of the unit of Fig. 1, with the cover or shield removed and portions broken away;

Fig. 3 is a fragmentary view of the grapple features of Fig. 2, with connected portions, shown as in thrown position;

Fig. 4 is a detail of frame-carried portions between the grapples, showing in dotted lines the ejected bottle-cap; and

Fig. 5 is a bottom plan view of the frame-carried portions of Fig. 3 and showing a portion of one of the grapples.

Advantageously, there may be selected a wall location 1 for bolts 2 to anchor an embodiment of the unit, say as equipped with an advertising display or sign 3. Under such circumstances this sign 3 may have to do with the source of the beverage or other item being dispensed, or may be adapted to variations or changes as the dispenser may deem appropriate.

The bolts 2 extend thru openings 4 in a frame 4' of laminated pole pieces for an electro-magnet or solenoid having a winding 5. Non-magnetic jacket portions 6 are provided for a core 7, with a spring 8 effective normally to locate the core 7 downward with its head 9 toward a diaphragm 10. A switch operating bar 11 is normally downward as held by a spring 12 to be clear of a plung-

2

er 13 of a micro type switch 14. Upon lifting of the bar 11 against the resistance of the spring 12, the switch 14 is closed and for such interval, the coil or winding 5 is energized and the sign 3 illuminated. The solenoid core 7 is then lifted.

The head 9 of the core 7 has a non-magnetic rocker 15 with a pivotal connection 16 thereto. The head 9 has an arcuate lower face 17 as clearance for the rocker 15 to shift in its holding of a pair of grapples or jaws 18, 19, having pivotal connections 20 with the rocker 15 adjacent opposite ends of the rocker 15. Openings 21 are centrally in the diaphragm 10 and are adjacent opposite sides of a seat 22 complementary to a disk type bottle cap 23 having a depending annular corrugated or fluted flange 24, in providing a seal as engaging a lip 25 for the neck of a bottle 26 in forming a closure therefor.

As toward each other and adjacent the rocker 15, the jaws 18, 19, have guide stems forming seats 27 for a compressible helical spring 28. The lower or free ends of the jaws 18, 19, have arcuate seat portions 29 concave toward each other and normally given yieldable spread by the compression spring 28.

The outward throw of the jaws 18, 19, as swinging away from each other in the openings 21 in the diaphragm 10, is adjustably limited by set screws 30 thru depending internally threaded lugs 31 from the diaphragm 10. These screws 30 may have polygonal recesses 32 at their outer ends permitting screw adjustment to act upon the lever jaws 18, 19, for wear take-up, as well as initial setting for the run of caps 23, 24, to be removed. The sealed bottle which has its cap thrust upward centrally of the pair of opposing arcuate portions of the seat 22, has the disk central portion of the seal or closure 23 against the bar 11. It does not require much pressure to lift this switch bar 11 and operate the switch 14, while the disk 23 of the cap is against a central projection 33 providing a guide for the bar 11.

The jaw arm 18 is guided by the opening 21 to register with the adjustable tapered tip of a set screw 30, at the initial or idle position for the device; that is, with the core 7 down or de-energized as to the solenoid coil 5. At this position of the arm 18, it has a cam or lug 34 in position to ride against the tip of the screw 30 as the core 7 ascends to pull the arm 18 therewith. This causes the seat 29 to ride toward the neck of the bottle 26 and lodge in coacting relation with the underside of the flange 24 as hanging over the lip 25. This action of the cam 34 is against the outward thrust of the spring 28.

Simultaneously with the ascent of the jaw arm 18, the arm 19 also rises. A cam portion 35 on the arm 19, causes the seat 29 to ride toward the bottle 26 and coat with the opposite side of the cap seal flange 24 to that engaged by the seat 29 of the arm 18. The fact that the arms 18, 19, have the rockable connection 15, 16, with the core 7, provides an automatic compensation for some range of bottle diameters. In fact the general yield elements as herein disclosed is such that the inward throw of the seats 29 is not sufficient to develop any bottle-fracture hazard.

The energizing of the coil 5 of the solenoid, in practice, gives a quick action in the upward pull effected through the core 7. In this transit, the cam 34 holds the jaw seat 29 of the arm 18 in engaging position with the flange 24 for being outwardly flared as the lug or projection 33 holds the disk central portion downward relatively thereto. However, as to the arm 19, the cam 35 is of less lineal extent than the cam 34, and the compression spring 28 tends to shift the seat 29 of the arm 19 clear of the already to-some-extent flared flange 24 of the bottle cap or crown seal. This outward movement of the seat 29 of the arm 19 is made more positive thru co-action with the inner end of the opening 21 by a cam 36 below the cam 35 and on the opposite side of the arm 19, as well as above the seat 29 to be clear of the cap 23, 24. From this position for the arm 19, the bottle 26 which had been snugly pulled and initially held against the projection 33, is now released and as taken by the dispenser clear of the decapper unit or device, the spring 12, thrust end portion 37 of the bar 11 to kick the distorted cap 38 clear of the seat 22, as the coil 5 is de-energized thru the bar 11 opening the switch 14. The deenergizing of the coil 5, allows the spring 8 to move the arms 18, 19, downward for the arms to be spread and the seat 29 of the arm 18 to move outwardly to their initial position. There is accordingly quick operation in clearing the decapper unit from the removed disk type of bottle seal as removed from the bottle. The dispenser, accordingly, without other effort than to locate the sealed bottle in sufficient proximity to the unit, is now to have such seal unseated by thrusting the end portion 37 of the switch bar 11 into position to close the switch 14. The operation occurs with such speed that the dispenser should retain hold of the bottle 26 and quickly clear the decapped bottle from the unit as the sign is off, for then the removed closure or cap is popped out clear of the device.

Adjustable legs 39 give supplemental adjustment range for the jaws of the unit in varying the location or spacing of the diaphragm 10 from the electromagnet.

What is claimed and it is desired to secure by Letters Patent is:

1. A sealed closure remover for container wherein the closure is a peripherally flanged disk, said remover comprising a seat having a central projection, a switch operating bar mounted in proximity to the seat for movement relatively to the seat, a spring normally thrusting the bar to extend beyond the projection in the seat whereby a sealing disk inserted in the seat will shift the bar against the action of the spring, a switch adapted to be closed by the movement of the bar by the disk, there being a circuit from the switch including a solenoid coil, a core actuatable by the coil, a pair of arms, at least one thereof mounted for movement relatively to the coil, said arms

each having opposing jaw seats at their free ends, spring means normally coacting between the coil and core to shift the core to inactive position as to the coil with the arms spread laterally from the seat, guide means adjustably mounted relatively to the coil and coacting to direct the arms to respond to core movement to swing into engaging position to pull the disk flange opposite portions to tend to dish the disk at the projection in the seat, said guide means including a throw out for one of the jaw seats, whereby the switch operating bar spring will then thrust the deformed flanged disk clear of the seat.

15 2. A bottle decapper for removing crimped crown caps from bottles, said decapper comprising a frame, a cap receiving seat at the bottom of the frame, power means in the top of the frame, said power means including an operating shaft, power control means fixed to the frame near the seat, an actuator bar for the control means, said bar slidably located within the seat and adapted to be shifted by insertion of a cap into the seat, a coil spring around the bar biasing the bar away from the control means, a pair of opposing grapples pivotally fastened to the operating shaft, guide means on the frame adjacent the seat for directing the grapples into engagement with the skirt edge of the cap for releasably deforming the cap skirt upon upward movement of the operating shaft, one grapple including a cam surface directed toward the seat whereby further upward movement of said shaft will cause said one grapple to be released from cap engagement and the action of said coil spring upon the actuating bar will eject the cap from said seat.

3. A bottle decapper for removing crimped crown caps from bottles, said decapper comprising a frame, a cap receiving seat at the bottom of the frame, power means in the top of the frame, said power means including an operating shaft, power control means fixed to the frame near the seat, an actuator bar for the control means, said bar being slidably located within the seat and adapted to be shifted by insertion of a cap into the seat, actuating means locating inactive position of the bar away from the control means, a pair of opposing grapples pivotally fastened to the operating shaft, guide means on the frame adjacent the seat for directing the grapples into engagement with the skirt edge of the cap for releasably deforming the cap skirt upon upward movement of the operating shaft, one grapple including a cam surface directed toward the seat whereby further upward movement of said shaft will cause said one grapple to be released from cap engagement and the action of said actuating means upon the actuating bar will eject the cap from said seat.

4. A decapper comprising a frame, a plunger reciprocally mounted in the frame, actuator means for reciprocating the plunger, said frame providing a seat for a cap, a pair of opposing arms pivotally connected to the plunger, said frame providing guide means coacting with and to direct the arms in one direction of plunger movement to engage and distort a cap at the seat, additional means connected to one of said arms and coacting with said frame for moving said one arm away from said cap on continued movement of said plunger to permit release of the distorted cap.

5. A decapper comprising a frame providing a seat for a cap to be removed, adjustable guide means in proximity to the seat, a plunger in and movable relatively to the frame, power means for

reciprocating the plunger, said plunger having a rocker at one end thereof, and a pair of relatively swingable arms mounted on the rocker and directed by said guide means in response to movement of the plunger in one direction of reciprocation to distort a cap at the seat, and means reacting against said arms, when said arms are moved in the other direction of reciprocation by the plunger, to spread said arms for insertion of a succeeding cap.
